CLAIM

The ornamental design for a key organizer, as shown and described.

DESCRIPTION

FIG. 1 is a top perspective view of a first embodiment of my new design for a key organizer.

FIG. 2 is a bottom perspective view of the key organizer of FIG. 1.

FIG. 3 is a side view of the key organizer of FIG. 1.

FIG. 4 is another side view of the key organizer of FIG. 1.

FIG. 5 is a top view of the key organizer of FIG. 1.

FIG. 6 is a bottom view of the key organizer of FIG. 1.

FIG. 7 is front view of the key organizer of FIG. 1.

FIG. 8 is a rear view of the key organizer of FIG. 1.

FIG. 9 is a top perspective view of a second embodiment of my new design for a key organizer.

FIG. 10 is a bottom perspective view of the key organizer of FIG. 9.

FIG. 11 is a side view of the key organizer of FIG. 9.

FIG. 12 is another side view of the key organizer of FIG. 9.

FIG. 13 is a front view of the key organizer of FIG. 9; and,

FIG. 14 is a rear view of the key organizer of FIG. 9.

The evenly-spaced broken lines shown in the figures illustrate portions of the key organizer which form no part of the embodiment in which they are shown. Randomly dashed lines represent surface shading.
